UNITED STATES PATENT OFFICE.

HENRY G. RAZALL, OF MILWAUKEE, WISCONSIN.

LOOSE-LEAF LEDGER.

SPECIFICATION forming part of Letters Patent No. 612,436, dated October 18, 1898.

Application filed May 10, 1897. Serial No. 635,848. (No model.)

To all whom it may concern:

Be it known that I, HENRY G. RAZALL, a citizen of the United States, and a resident of Milwaukee, in the county of Milwaukee and 5 State of Wisconsin, have invented certain new and useful Improvements in Loose-Leaf Ledgers; and I do hereby declare that the following is a full, clear, and exact description thereof.

My invention has especial reference to that 10 class of blank books known as "loose-leaf ledgers" wherein the leaves are removable at pleasure, so that the leaf or leaves for any account can be added to or transferred at any time, thus doing away with the necessity of 15 employing a series of ledgers for the open accounts; and my said invention consists in certain peculiarities of construction and combination of parts, as will be fully set forth hereinafter and subsequently claimed.

20 In the drawings, Figure 1 is a vertical sectional view of a device embodying my present improvements, taken on the line 1 1 of Fig. 3. Fig. 2 is a longitudinal sectional view on the line 2 2 of Fig. 3. Fig. 3 is a detail view, with the cover partly broken away and partly in section, on the line 3 3 of Fig. 1. The foregoing figures illustrate one form of locking device. Fig. 4 is a perspective view of the entire device. Fig. 5 is a detail view 25 showing another form of the locking device.

Referring to the drawings, A B represent, respectively, the upper and lower covers of my device, said covers having separable backs 30 *ab*, adapted to slide past each other, as shown, and reduced flexible portions *c c* adjacent to the back of the device to enable the said covers to be readily opened and thrown back when the device is in use.

C D D are hollow columns, polygonal in 40 cross-section, secured to the cover B back of the described flexible portion *c* and between the same and the back *b*, the preferred form of said columns in section being that of the lozenge and the base of each column being preferably solid and formed with a projecting 45 flange *d* all around the same to better secure the said columns in place in the said cover B, through which they project, as shown in Figs. 1 and 2, and to guard against the column C being drawn up out of place under pressure, 50 as hereinafter explained. The columns D D

are open-topped; but the column C has a closed top *e*, with a screw-threaded bore there-through, forming, in effect, a nut.

E E are columns secured to the cover A in 55 the same manner as the columns D D are secured to the cover B, and the said columns E E are likewise polygonal in cross-section and of a size and shape to fit and telescope within the columns D D.

F is a hollow column secured in like manner to the other columns to the cover A, said column F being of a size and shape in cross-section to receive and telescope over the column C.

G is a screw adapted for engagement with the nut *e* in the column C, and said screw being preferably formed with an enlarged head H, terminating in an upper squared end I, which projects up through the open upper 60 end of the column F. The head H of the screw, which is either integral or otherwise rigid with the balance of said screw, is formed with an annular exterior groove *f*, and pins *g g* extend transversely through the said column F and engage with said groove *f*, whereby when the screw G is revolved by an ordinary clock-key (not shown) fitting on the described square upper end I of the screw the latter is prevented from being screwed up or 65 down and exerts its force in the said nut *e* to either increase or decrease the distance between the covers A B, according to the direction in which the said screw G is revolved, in an obvious manner.

J is a lock, of any suitable construction, secured to a recess in the cover A and provided with a bolt K, which is adapted to engage with some part of the screw G to prevent the movement of the latter. In the drawings I 70 have shown two ways of locking the said screw. In the form shown in the first three figures the head H of the screw is provided with a series of sockets or keepers *h* to receive the end of the bolt K, as shown, and in Fig. 5 75 the end of the bolt K is formed with a square-edged recess *i* to receive the squared top end I of the screw G when the said bolt is shot forward. Either form may be employed, as preferred, it being only necessary in the first 80 instance that one of the sockets *h* shall be in line with said bolt and in the second instance 85

that the end I shall be squarely presented in line with the square recess *i* of said bolt.

5 *L* represent the leaves of my ledger, which are designed to be printed and ruled like any ordinary ledger-leaves, but which at their inner ends are formed as best shown in Figs. 2 and 3. A piece of any suitable thin fabric *j* is secured to the inner edge of each leaf *L*, and the extreme outer edge or end of this 10 fabric is reinforced by additional layers of like fabric applied on each side of the fabric *j*, as shown at *k k*. The inner or rear end edge of the reinforced attachment to each leaf is cut in line with each of the described columns *D F D* with the notches *m*, the cut continuing in a straight line *n*, and then the opening is extended to a shape and size sufficient to take in the said columns, as shown at *o*.

20 The operation of my device will be readily understood from the foregoing description of its construction taken in connection with the accompanying drawings. Let it be understood that the ledger is in the complete and 25 locked condition shown in Fig. 4. Now suppose it is desired to either remove or insert a leaf *L*. While the ledger is so locked no change in its leaves except a forcible tearing or cutting out is possible, and this would 30 instantly show by the stub of the leaf still locked to place. The key of the lock *J* is inserted and turned and the bolt *K* thereby withdrawn from engagement with the screw *G*. Then a clock-winding key is fitted on the end *I* of 35 said screw and turned so as to increase the distance between the covers *A* and *B*. If a leaf *L* is now to be removed—as, for instance, when the account on said leaf is closed—a sharp pull on this leaf will instantly detach 40 it, as the slits at *n* are sufficient to enable the leaf to be pulled from contact with the described columns *D E C F* without injury to the leaf or disturbance of the leaves above or below the leaf being removed. If, on the contrary, 45 an account is still open, but the entries on the leaf of said account have covered the same, a fresh leaf can be inserted for the continuation of said account by placing this new leaf next the one just filled, with the notches 50 *m* of the new leaf against the adjacent angles of the described hollow columns and giving a push to the leaf, when the slits *n* will open and permit the larger openings *o* to receive the said columns and the new leaf is in place. 55 In either event the clock-key is then applied to the screw *G* and turned to again force the covers *A B* toward each other, care being taken to leave the screw *G* in proper position—that is, with one of the keepers or sockets *h*, 60 in the form shown in Figs. 1 to 3, or with one of the square faces of the end *I*, in the form shown in Fig. 5, in line with the bolt *K*—when the covers are brought toward each other to the required point, so that all the leaves are 65 tightly clamped again, and then the key is turned in the lock *J* and the bolt shot into engagement with the upper part of said screw

G, so that when said lock-key is taken away the ledger cannot be tampered with.

Having thus described my invention, what 70 I claim as new, and desire to secure by Letters Patent, is—

1. In a loose-leaf ledger, the combination of a pair of independent covers, a series of hollow columns secured to each cover, in line 75 with each other, and each column on one cover adapted to telescopically engage with the opposing column on the other cover, one of said columns being provided with a nut, and the opposed column having a screw secured therein for engagement with said nut, 80 said screw being capable of revolution but incapable of independent longitudinal movement.

2. In a loose-leaf ledger, the combination 85 of a pair of independent covers, a series of polygonal hollow columns secured to each cover, those on one cover being adapted to telescopically engage with the opposing columns on the other cover, a nut in one of said 90 columns, and a revoluble screw in the opposed column held against independent longitudinal movement, and adapted for engagement with said nut.

3. In a loose-leaf ledger, the combination 95 of a pair of independent covers, a series of hollow columns secured to each cover, those on one cover being adapted to telescopically engage with the opposing columns on the other cover, a nut in one of said columns, a 100 revoluble screw held against independent longitudinal movement in the opposed column and adapted for engagement with said nut, and a lock secured to one of said covers and provided with a bolt adapted to engage 105 with said screw and prevent the revolution thereof.

4. In a loose-leaf ledger, the combination of a pair of independent covers, a series of hollow columns secured to each cover, those 110 on one cover being adapted to telescopically engage with the opposing columns on the other cover, a series of loose leaves each leaf having a series of openings adjacent to one 115 end edge thereof of a size and location corresponding to that of said columns and said leaves being cut or slitted between said openings and said adjacent edge, a nut in one of said columns and a revoluble screw held against independent longitudinal movement 120 in the opposed column, and adapted for engagement with said nut.

5. In a loose-leaf ledger, the combination of a pair of independent covers, a series of hollow columns secured to each cover, those 125 on one cover being adapted to telescopically engage with the opposing columns on the other cover, a series of loose leaves each leaf having a series of openings adjacent to one 130 end edge thereof of a size and location corresponding to that of said columns and said leaves being cut or slitted between said openings and said adjacent edge, a nut in one of said columns, a revoluble screw held against

independent longitudinal movement in the opposed column and adapted for engagement with said nut, and a lock secured to one of said covers and provided with a bolt adapted 5 to engage with said screw and prevent the revolution thereof.

In testimony that I claim the foregoing I

have hereunto set my hand, at Milwaukee, in the county of Milwaukee and State of Wisconsin, in the presence of two witnesses.

HENRY G. RAZALL.
